UNITED STATES PATENT OFFICE.

FREDERICK HAGGER HEADLEY, OF NORTHFIELD, NEAR BIRMINGHAM, ENGLAND.

PERAMBULATOR AND THE LIKE.

Application filed May 28, 1923, Serial No. 642,000, and in Great Britain August 17, 1922.

The present invention has relation to perambulators and the like more especially those of a collapsible or semi-collapsible character and in which the handle is adapted 5 to be pivoted or moved into adjacency with the frame when out of use. The present improvements are however applicable to perambulators of a rigid or permanently extended character.

10 According to the present invention the handle is of a detachable character adapted to be assembled at either extremity of the vehicle and supported by a jointed stretcher bar or fixing strut pivoted or connected to the handle 15 and to the vehicle frame at a position midway between or intermediate its (the vehicle frame) extremities. By so mounting the handle the vehicle can be propelled with the seat facing forwardly or rearwardly.

20 Further features of the present invention are hereinafter described and claimed.

In order that this invention may be clearly understood and readily carried into practice, reference may be had to the appended 25 explanatory sheet of drawings, upon which:—

Figure 1 is a perspective view of a perambulator constructed according to the present invention, the handle being placed with the seat facing forwardly.

30 Figure 2 is a side elevation of the present perambulator, the handle being placed for propelling the vehicle with the seat facing rearwardly.

Figures 3 and 4 illustrate in front elevation 35 and vertical section the fastening means of the handle.

In a convenient embodiment of the present invention the frame of the vehicle involves two parallel side stays 1 to which are pivoted 40 collapsible parallelogram constructions 3, 4, 5, from which the seat is suspended and which are adapted to be collapsed into adjacency with the side stays 1 of the frame together with the seat which is for its main part of a 45 flexible character. Each parallelogram construction involves a horizontal stay indicated by numeral 3, and forward and rearward stays indicated by numerals 4, 5 arranged at a slight inclination and pivoted to the side stays 1 of 50 the frame. These parallelogram constructions 3, 4, 5, are adapted to be held in the extended condition by means of jointed stretcher bars 6 arranged diagonally as shown in Figures 1 and 2.

55 An inverted U-shaped handle 7 is employed the limbs of which are flattened at their ex-

tremities and perforated at 8 (see Figure 4), and adapted to be engaged with headed studs 9 provided in pairs at each end of the vehicle frame. A jointed stretcher bar 10 is 60 employed upon each side of the vehicle for supporting the handle in the in-use position and each bar is pivoted at a mid-way position 11 along the frame and is pivoted to the handle at a point 12^a substantially mid-way 65 along its length.

By springing the limbs of the handle 7 apart the same may be disengaged from the studs at one extremity and the handle may be engaged with the studs at the opposite extremity the same stretcher bar 10 enabling the handle to be rigidly retained in the in-use position at either end of the vehicle. These stretcher bars 10 one of which is disposed at each side of the vehicle are adapted to permit 75 of the passage of the handle on the outside thereof and such stretcher bars are preferably permanently combined with the handle and vehicle frame and prevent the complete separation of the handle from the frame. 80 The handle 7 at a position substantially midway along its length conveniently at the point 12^a is provided with an inwardly projecting grooved stud 13 adapted to engage a slot (see Figs. 1 and 2) in the upper extremity of the 85 rearward strip 4 of the parallelogram in each instance. In this manner when the handle 7 is in the position shown in Figure 1, and after "breaking" the stretchers 6 and 10 and moving or swinging the handle 7 forwardly and 90 downwardly the parallelogram construction may be collapsed with the handle in a position adjacent the frame 1.

In order to retain the handle ends or extremities in engagement with the studs 9 95 aforementioned, the latter are provided with annular grooves 10^a (Figure 4), and pivoted at 11^a to the outer face of the handle is a fastening strip or lever 12 which has a key-hole shaped slot 13 the larger part of which is adapted to pass over the head 14 and the smaller part adapted to engage the annular groove 10^a aforesaid and such strip is retained in the positions shown in Figures 3 and 4 by a small projection 15 pressed up 100 from the strip and adapted to be sprung over the curvature of the ends of the handle 7. To disengage said handle ends or limbs 7 from the stud 9 the strip 12 is swung from the position shown in Figure 3 until the large 105 part of slot 13 comes opposite head 14 when said handle end can be readily removed.

Slot and projection mechanism 16, 17 limits the movement of the strip 12. Such a fastening strip 12 is provided in connection with each end of the handle and moves therewith 5 when the handle is transferred from one end of the vehicle to the other.

In order to disengage the handle 7 from the parallelogram structure 3, 4, 5, on the extremity of the vehicle the stretcher bar 10 associated with the handle and the stretcher bar 6 associated with the parallelogram structure 3, 4, 5, are first broken. The fastening strips 12 are then swung about the pivots 11^a and the handle then disengaged from the 15 studs 9 after which the studs 13 upon the handle are disengaged from the slots in the upper part of the parallelogram members 4. The handle 7 can then be transferred to the other extremity of the vehicle and applied 20 to the studs 9 thereon and then braced as shown in the Figure 2. In either position said handle may be collapsed into a position adjacent the frame 1. When in the position shown in Figure 1 the handle is collapsed 25 with the structure 3, 4, 5, and when in position shown in Figure 2, said structure is first collapsed and then the handle, or the handles, may be partially collapsed from the position shown in Figure 2 onto the extended structure 3, 4, 5.

What I claim as my invention, and desire to secure by Letters Patent is:—

1. In a device of the class described em-

bodying therein a frame, laterally extending studs on the ends of said frame, a handle bar having side members with apertures in the bottom ends thereof adapted to be engaged over said studs which project beyond the same, and a lever pivoted to the end of each side member and adapted to be engaged with the projecting end of an associated stud to detachably lock said handle bar side member thereto.

2. In a device of the kind described embodying therein a frame member, a laterally extending stud thereon, a handle bar member, a lever pivoted thereon and having a key hole slot adapted to receive said stud and to lock the handle member thereto when said lever is in a position parallel with said handle bar member, and means for securing said lever in this last mentioned position.

3. In a device of the kind described embodying therein a frame member, a laterally extending stud thereon, a handle bar member, a lever pivoted thereon and having a key hole slot adapted to receive said stud and to lock the handle member thereto when said lever is in a position parallel with said handle bar member, means for securing said lever in this last mentioned position and means for limiting the swinging movement of the lever.

In witness whereof I have hereunto set my hand.

FREDERICK HAGGER HEADLEY.
